UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,941, dated June 24, 1890.

Application filed April 15, 1890. Serial No. 348,117. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

15 A is the body part, and is formed with curved walls increasing outward as we ascend, and surmounted with a cap B of plain surface, having a curved or annular swelling boundary C, formed in the shape of depending leaves by suitable ornamentation. Between the 20 part C and the body part A is an annular band D of ornamental work.

F is the base part, and consists of a large

band of ornamental work bounded on the top by a smaller band G of plain surface and on the bottom by a small cylindrical band H of plain surface.

25 The body part A is ornamented by having alternate vertical bars of plain surface I and ornamental work E, and in which the plain surface I is depressed to a slight extent.

The handle is made of any suitable material.

Having now described my new design, what I claim as new, and desire to secure by Letters Patent, is—

35 The design for cane or umbrella handles, substantially as herein described and shown.

In testimony of which invention I have hereunto set my hand.

HENRY O. SCHMIDT.
